Leo Wertheimer, Buffalo, N. Y., assignor to Am-
coin Corporation, Buffalo, N. Y., a corporation
of New York

Application April 23, 1948, Serial No. 145,915

Term of patent 14 years

(Cl. D52—1)

To all whom it may concern:

Be it known that I, Leo Wertheimer, a citizen
of the United States, residing at Buffalo, in the
county of Erie and State of New York, have in-
vented a new, original, and ornamental Design
for a Regulator for Liquid Dispensing Device, of
which the following is a specification, reference
being had to the accompanying drawing, forming
part thereof.

Fig. 1 is a front elevation of a regulator for
liquid dispensing device embodying my new
design;

Fig. 2 is a side elevation thereof; and
Fig. 3 is a plan view thereof,

I claim:

The ornamental design for a regulator for
liquid dispensing device, as shown.

LEO WERTHEIMER.
